UNITED STATES PATENT OFFICE.

HERBERT M. SMALL, OF BALDWINSVILLE, MASSACHUSETTS, ASSIGNOR TO
SARAH ELIZABETH SMALL, OF SAME PLACE.

MANUFACTURE OF CARPET-PADS.

SPECIFICATION forming part of Letters Patent No. 231,733, dated August 31, 1880.

Application filed March 22, 1880. (No model.)

To all whom it may concern:

Be it known that I, HERBERT M. SMALL, of Baldwinsville, of the town of Templeton, of the county of Worcester and State of Massachusetts, have invented a new and useful Improvement in the Manufacture of Carpet-Pads; and I do hereby declare the same to be described in the following specification and represented in the accompanying drawings, of which—

Figure 1 is a top view, Fig. 2 a longitudinal section, and Fig. 3 a transverse section, of a carpet-pad of my improved kind having to its sectional pads a single covering-sheet. Fig. 4 is a longitudinal section of it as made with two covering-sheets to its sectional pads.

This carpet-pad is composed of a series of separate sectional pads, as hereinafter described, arranged and combined with a paper covering sheet or sheets disposed and applied as explained; and, furthermore, such pad is or may be provided with strengthening threads or twines arranged along the ends of the sectional pads and covered by the covering sheet or sheets.

Each of the sectional pads A consists of a flat tube of paper, (or a narrow sheet of paper folded in the form of a flat tube,) and having within it a stuffing of a fibrous material. Fig. 5 is a transverse section, and Fig. 6 a longitudinal section, of such a pad, *a* being the paper tube or wrapper, and *b* the stuffing of fibrous or elastic material, such as is commonly employed in making carpet-pads. A series of these long and narrow pads I arrange edge to edge, or nearly so, and parallel to each other upon a paper sheet or covering, B, preferring to have the joints or laps of the wrappers or tubes of the sectional pads next to such cov-

ering-sheet. The said covering-sheet, having the sectional pads arranged on and across it, has a width greater than the length of each of the sectional pads, each of which is to be alike in length, and they are to be cemented at suitable intervals down upon the covering-sheet, which, at or near its edge, is to be folded over the next adjacent ends of the sectional pads and down upon the upper surfaces of such pads and cemented or pasted thereto, a line or twine, C, being first laid in each of the folds of the covering and against the ends of the sectional pads. This line or twine is to strengthen the carpet-pad at its edges.

If desirable, an auxiliary covering, D, or paper sheet may be arranged on the sectional pads and the laps of the main covering and be pasted or fastened thereto.

A carpet-pad so made can be easily folded for storage or transportation. The material composing the stuffings of its pads is completely covered, so as not to be liable to get out of place or drop out of the sectional pads at their ends.

What I claim as my invention is as follows, viz:

1. A carpet-pad composed of a series of sectional pads, as described, and a covering of paper, all combined and arranged substantially as specified.
2. A carpet-pad composed of a series of sectional pads, as described, strengthening lines or twines, and a covering of paper, all combined and arranged substantially as set forth.

HERBERT M. SMALL.
